(57) **CLAIM**

The ornamental design for a magnet for attachment to a capacitor, substantially as shown and described.

DESCRIPTION

FIG. 1 is a front perspective view of a magnet for attachment to a capacitor;

FIG. 2 is a front view thereof;

FIG. 3 is a rear view thereof;

FIG. 4 is a right-side view thereof;

FIG. 5 is a left side view thereof;

FIG. 6 is a top view thereof;

FIG. 7 is a bottom view thereof; and,

FIG. 8 is a rear perspective view thereof in a broken line environment.

1 Claim, 3 Drawing Sheets
